UNITED STATES PATENT OFFICE.

KUNISUKE SUYEHIRO, OF EUREKA, UTAH.

DOLL-HOUSE.

1,343,065.

Specification of Letters Patent.

Patented June 8, 1920.

Application filed January 4, 1919. Serial No. 269,560.

To all whom it may concern:

Be it known that I, KUNISUKE SUYEHIRO, a subject of the Emperor of Japan, residing at Eureka, in the county of Juab and State 5 of Utah, have invented a new and useful Doll-House, of which the following is a specification.

This invention relates to doll houses, and more particularly to that class which is 10 capable of being folded or knocked down for the purpose of storage or for shipment in large quantities so as to occupy a small space.

The principal object is to provide a toy 15 or doll house of this character which may be easily set up in the form of a house by a child or other person, and having certain foldable and detachable parts which may be nested into a compact form.

20 Another object is to provide such a toy having all the external appearance of a genuine house and, at the same time, having means for ready access to the interior thereof, in order that the same may be in constant view and that articles such as dolls 25 and miniature furniture, etc., may be readily placed therein or removed when it is desired to collapse the house.

A full and complete understanding of the 30 invention may be obtained from a consideration of the following detailed description, taken in connection with the accompanying drawings forming a part of this specification; it being understood that while 35 the drawings show a practical form of the invention, the latter is not confined to strict conformity therewith, but may be changed or modified, so long as such changes or modifications mark no material departure 40 from the salient features of the invention, as specifically pointed out in the appended claims.

In the drawings, in which like reference 45 characters designate similar parts throughout the several figures—

Figure 1 is a perspective view of the doll house as it appears from the front thereof;

Fig. 2 is a similar view of the same as it appears from the rear thereof;

50 Fig. 3 is a perspective view of the house in folded or knock-down position;

Fig. 4 is a detail horizontal sectional view 55 through one corner of the house, adjacent to the front porch when the same is in set-up position; and

Fig. 5 is an elevation of a portion of a slightly modified form of the structure.

Many doll houses of intricate structure have been devised having removable walls, or removable stories, etc., requiring interlocking means and other features that cause the same to be so expensive as to be beyond the reach of the average person, and at the same time such houses, while very pleasing to the eye and entertaining to the child, have the disadvantage of being inaccessible, thus rendering it impossible for the child to dispose or arrange dolls, furniture, etc., at will within the rooms of the house. In addition to this, such houses are often easily broken 60 and in many cases are soon tired of, thus causing a useless expenditure for a costly toy. Great demand is felt for a simple, cheap article of this class having all the necessary features in imitation of a real 65 house, and which may be manufactured of common materials and in such a simple manner as to be sold at an extremely low cost.

The present invention is designed to fill 70 such a demand, and by the employment of the parts hereinafter enumerated and described, it has been found that a very pleasing and efficient toy house of this class has been provided having the advantages stated 75 above.

The front wall 1 is shown as of a familiar type of house front having its upper edge formed into an apex and extending upwardly in imitation of a gabled roof and 80 provided in proper spaced relation to the ground line with representations of lower-floor windows 2—2, while located in the upwardly-extending portion thereof is a similar representation of an upper-floor 85 window 3, having a small portico 4 arranged around the lower part thereof.

The front wall is preferably formed of heavy stiff pasteboard, and is provided with a marginal border, preferably formed of 90 wooden strips 5, extending entirely around the front wall and having suitable grooves or kerfs 6 into which the marginal edges of the pasteboard comprising the front wall 1 are seated and secured as by gluing, or in 95 any other suitable manner. The wooden strips 5 serve to strengthen and stiffen the structure and also provide suitable means for the attachment of certain parts to be described.

A similar wooden strip 7 extends across the front wall 1 and joins the vertical strips arranged at the sides of the front and at their points of juncture with the inclined 5 roof strips and serves to stiffen the front at an elevation above the ground line.

Brackets 8—8 arranged beneath the said portico 4 are suitably secured to the horizontally-disposed strengthening strip 7 and 10 serve to hold the said portico securely in place.

The wooden strips 5—5 comprising the roof timbers are adapted to support relatively narrow roof members 9—9 formed of 15 strips of wood, beveled at their upper, abutting ends, at 10—10, to represent the gable of the roof, and having their upper surfaces painted to represent shingles in imitation of a common style of roof. These members 20 9—9 may be secured to the adjacent inclined strips 5—5 by small nails 11—11 which may be easily withdrawn, or by simple pins fitting in suitable sockets. Furthermore, the members 9—9 may be hinged together at 25 their beveled ends 10—10, in which event they may be satisfactorily held in place without the use of nails or pins.

A front door 12 is preferably located between the lower windows 2—2 and is suitably hinged so as to swing inwardly or outwardly as desired.

Secured to the outer edges of the vertical marginal strips 5—5, as by a flexible strip of paper or cloth 13, as indicated in Fig. 4 35 of the drawings, are oppositely disposed porch members 14—14 composed of pasteboard and suitably scored at an intermediate point along a vertical line and adapted to be bent to form each an end wall 15 and a 40 front wall 16, the end walls being inclined along their upper edges, as shown at 16^a, to form a support for the roof member 17 of the front porch.

The roof member 17, which is formed of 45 pasteboard is somewhat wider at its front edge than at its rear edge, where the same is hinged to the lower edge of the horizontally disposed stiffening strip 7, as by a strip of cloth or paper in the same manner as the 50 porch member 14—14, and is adapted to be folded down over the latter after the same are swung inwardly to lie flat against the front face of the house-front 1, as illustrated in Fig. 3 of the drawing.

55 The porch roof 17 is likewise painted to represent shingles upon the upper surface thereof, and is further provided with a plurality of alined slots 18 arranged adjacent to the front edge thereof in a position to receive upwardly extending tongues 19 formed integrally with the front portions of the porch members 14 and arranged at the inner and outer edges thereof. These tongues serve to securely hold the roof in position 60 and prevent the porch members 14 from

moving from their angularly bent position, with their lower edges resting on the floor or other support, thus forming a partially inclosed porch, the inner opposed edges of the members 14 being spaced apart to form 70 an entrance opposite or in front of the aforesaid door 12.

The end and front panels of the porch members 14—14 are cut out as indicated at 20 and 21 respectively, thus forming intermediate angular corner posts 22 and inner terminal posts 23, all of which serve to maintain the porch roof in position. The panels, below the respective cut out portions 20 and 21 are painted to represent a 80 rail and vertical bars in imitation of those in common use.

Side walls 24, composed of pasteboard and having their marginal edges secured to interfitting wooden strips 25, in the same manner as the house front 1 are secured, preferably by metallic hinges 26, to the rear edges of the vertical wooden strips 5 of the front 1 and are adapted to extend, when the house is in set-up position, as illustrated in Fig. 1 90 of the drawings, in a rearwardly direction and at right angles to the front for the purpose of forming an inclosure therebetween, wherein dolls and miniature furniture may be manipulated at the pleasure of the child 95 engaged in playing with the toy. These side walls, which are only as high as the height of the vertical portion of the front 1 may have representations of windows, as at 27, and other ornamentation, such as vines, etc. 100 placed thereon wherever desired, and they are adapted when in folded position, to lie flat against the rear face of the front 1, as shown in Fig. 3, a supplemental strip 28, of equal thickness to the marginal strips 25 of 105 the side walls, being interposed between the front edge of one of said side walls and the adjacent edge of the front 1, to which the adjacent hinges are secured, in order to provide the necessary space for the other side 110 wall to be folded therebetween, as will be understood.

In order to render the interior of the inclosure more accessible the rear wall of the house or room is left open, to be closed by 115 a pair of curtains 29, reaching to the floor or other support and suitably hemmed as at 30, along their upper edges, for the reception of a curtain-supporting wire rod 31, having its ends bent to form spring clips 32 which 120 are sprung over the top edges of the side walls, near their rear extremities to perform the double function of supporting the curtains 29 and to hold the side walls rigidly in right-angular relation to the front wall 1 125 of the structure, the wire composing the rod being of sufficient stiffness for such purpose.

In Fig. 5 of the drawing there is illustrated a slightly modified form of the invention, wherein the front wall is divided 130

into two vertical sections 1^a—1^a having the marginal stiffening strip as in the first-described form and adapted to be secured together, by removable pins traversing alined 5 eyes 33. The side walls, hinged to the front, as at 26^a—26^a, are in turn vertically divided into two sections 24^a—24^a and hinged together as at 34—34 so that, when desired, the entire structure may be compactly folded 10 into a small bundle for storage or shipping.

From the foregoing, it will be seen that a simple and attractive toy house has been devised, which may be manufactured from the cheapest materials, and sold at a minimum 15 price, and that the same may be easily knocked down or set up by a child, it being only necessary when folding the same, to unsheat the tongue 19 from their inserted positions within the slots 18 and to fold the members 20 14—14 one upon the other against the front face of the house front 1, and then to remove the wire member 31 together with the curtains, from engagement with the sides 24—24, when the latter may be in like manner 25 folded against the rear face of the member 1, and after removing the roof members 9—9, the same may be placed together with the curtains and the rod beneath the folded side walls and safely placed away for further 30 use, or may be advantageously packed in quantities for shipment.

The doll house may be made in many different styles, as will be readily understood and still retain the features of the 35 present invention, and in the case of larger houses it may be found advisable to make the entire structure of wood, in which event it might be desirable to form the windows by actual openings, instead of merely representing the same, as in the illustrated 40 form of the invention, and to supply panes of isinglass or other material and to provide shutters for the same. In this form of house it would also be advisable to form 45 the porch of wooden pieces, hinged together with metallic hinges and the entire structure coated by suitable waterproof paint so that the same can be washed and kept in a clean condition.

50 I claim as my invention:—

1. A doll house comprising a front wall shaped and ornamented to simulate the front of a house having a porch and porch roof, and constructed so as to be supported 55 upon a floor, rearwardly extended side walls hinged at their front edges to the opposite front edges of the front wall so as to fold inwardly and adapted to be folded flat one upon the other against the rear face of 60 the front wall, said side walls being shaped

and ornamented to simulate the sides of a house and resting at their lower edges upon the floor, and spaced apart at their rear ends, a curtain for closing the space between the rear ends of the side walls, and 65 a rod for supporting the curtain, the said rod being provided with a spring clip at each end, said clip being sprung over and engaging with the top edges of the side walls, so as to hold the side walls rigidly 70 in proper relation to the front wall of the structure.

2. A doll house comprising a front wall, rearwardly extending side walls hinged at their front edges to the opposite side edges 75 of the front wall and adapted to be folded against the rear face thereof, foldable porch members hinged at their rear edges to the front face of the front wall and at the opposite side edges thereof, said porch 80 members having hingedly connected end and front walls, tongues extending upwardly from the said front portions, a porch roof hingedly connected to the front face of the front wall for vertical swing- 85 movement and provided with alined slots for the reception of said tongues when the porch members are in open position, a rod having terminal clips for engagement with the upper edges of the side walls 90 near their rear ends, and curtains hung on the rod to form the rear wall of the enclosure.

3. A doll house comprising a front wall, foldable porch members hinged to the opposite edges of the same and adapted to be folded flat against the front face thereof, each porch member being composed of an end and a front portion vertically hinged together to form angularly bent corners, 100 each front portion having upstanding tongues, a horizontally disposed porch roof hinged for vertical swinging movement to the front face of the front wall and having alined slots for the reception of the 105 tongues when the porch is in extended position, foldable side walls hinged to the rear face of the front wall and at the opposite side edges thereof, said walls being adapted to be folded flat against the rear face of the 110 front wall or to be extended at right angles thereto, and a curtain supporting rod engaging with said walls to maintain them in extended position.

In testimony that I claim the foregoing 115 as my own I have hereto affixed my signature in the presence of a witness.

KUNISUKE SUYEHIRO.
